UNITED STATES PATENT OFFICE.

RUFUS W. SCOTT, OF NEW YORK, N. Y., ASSIGNOR TO HEMPHILL COMPANY, OF CENTRAL FALLS, RHODE ISLAND, A CORPORATION OF MASSACHUSETTS.

SEAMLESS STOCKING AND METHOD OF MAKING SAME.

Application filed October 21, 1922. Serial No. 596,133.

To all whom it may concern:

Be it known that I, Rufus W. Scott, a citizen of the United States, and a resident of the city of New York, in the county of New York and State of New York, have invented an Improvement in Seamless Stockings and Methods of Making Same, of which the following description, in connection with the accompanying drawings, is a specification, like characters on the drawings representing like parts.

This invention relates to seamless stockings and to the method of making the same. In order that the principle of the invention may be readily understood, I have disclosed certain embodiments of the stocking of my invention in the accompanying drawings, wherein—

Fig. 1 is a side elevation of a seamless stocking embodying my invention;

Fig. 1^a is an enlarged and somewhat diagrammatic detail indicating a mock seam formed by draw stitches.

Fig. 2 is an enlarged and somewhat diagrammatic detail showing the manner of forming a part of the back of the stocking;

Fig. 3 is a view similar to Fig. 2 but of a somewhat modified form of my invention;

Fig. 4 is a similar view of still another form of my invention; and

Fig. 5 is a similar view of still another form of my invention.

The stocking of my invention is a so-called circular or seamless knit stocking knitted upon a circular machine having means for forming the heel and toe pockets, such as narrowing and widening pickers. While any suitable mechanism may be employed in the production of the stocking, the machine should be equipped with means for introducing the main knitting yarn or thread and for introducing a reenforcing yarn or thread at the desired point or points and desirably with means for changing the stitch length as the knitting progresses.

My invention pertains more particularly to a structural variation in the knitting of the stocking, in combination with a reenforcing stripe, which features are so coordinated as to simulate certain full fashioned stockings notably those wherein the selvaged edges of the leg portion thereof are reinforced, certain advantages hereinafter pointed out being obtained by the employment of

a structural variation in the character of the knitting as a mock seam.

While the principle of my invention involving the coordination of a structural variation in the character of the knitting so as to form a mock seam during the knitting operation, and the stripe produced by an auxiliary or reenforcing yarn or thread, may be applied at any desired part of the stocking or other fabric, it is obvious that the simulation referred to can be best achieved by forming the same at the back of the leg of the stocking and accordingly such embodiment of the invention is herein disclosed and will be sufficiently described without limiting the invention strictly thereto. The structural variation to produce a mock seam during the formation of the stocking is desirably a tuck stitch formation, although other structural stitch changes may be employed, such for example as draw stitches. I preferably employ tuck stitches and in order to emphasize the effect thereof, I may form two or other pluralities of vertical rows of tuck stitches, which rows may adjoin or which may be separated by a single line of regular stitches in the event that I employ two vertical rows of tuck stitches or which may be separated from each other by a single line of regular stitches at each side of the intermediate line of tuck stitches if three lines or wales of tuck stitches be employed. Other forms of my invention are clearly comprehended within the scope thereof as, for example, a single line or wale of tuck stitches. In all cases however, the reenforcing yarn or thread is inter-knitted into and forms a structural part of the tuck stitches, and also of the line or lines of regular stitches between the lines of tuck stitches if such line or lines of regular stitches be utilized. Certain important advantages grow out of such structure and certain of them will be hereinafter pointed out.

The stripe which preferably extends upon both sides of the line of tuck stitches is desirably formed by introducing an auxiliary or so-called reenforcing yarn or thread in any known manner, beginning at or near the upper end of the stocking and for any suitable width as, for example, from six to ten wales upon each side of the line or lines of tuck stitches, and also extends desirably

- throughout and is incorporated into the tuck stitches themselves. This result I have best accomplished by inter-knitting the auxiliary or reenforcing yarn or thread from edge to edge of the stripe and then floating the same back upon the inside of the fabric to the commencement edge of the stripe and repeating this operation throughout the formation of the entire stripe, the said floating portions of the yarn or thread being entirely disassociated from the tuck stitches or other structural variations constituting the mock seam, but lying smoothly against the inner face of the stripe at the inside of the stocking and in parallelism with each other and not disarranged with respect to each other as would be the case were a mock seam of sewing machine stitches employed instead of the described structural variations.
- 20 Referring more particularly to the drawings, the stocking is indicated generally at 1, it having desirably a seamless heel 2 and toe 3, a high splice 4 of any suitable shape being provided in the knitting operation by introducing a reenforcing yarn or thread which may be the same yarn or thread as that employed for knitting the longitudinal stripe, or a substitute yarn or thread.

The stocking may be knitted from any suitable material, as for example silk, and beginning at or near the upper end of the stocking as, for example, at the bottom of the so-called welt portion, I introduce a reenforcing yarn or thread which may be fed to the needles in any suitable manner, as, for example, by a special yarn finger at some point where the needles are divided by a special cam so that the needles which are not to take the auxiliary yarn or thread are either elevated or depressed, and the auxiliary yarn or thread is delivered to the other needles including the tuck stitch needles, which total number of needles receiving the reenforcing yarn or thread may be of any desired number as, for example, from six to ten at each side of the back median line of the stocking.

In Fig. 2 I have represented the main yarn at 5 and the auxiliary yarn or thread at 6 and, for convenience of illustration merely, have represented the two yarns or threads as incorporated into the knitting at three wales only beyond the tuck stitch wales at each side thereof, it being obvious that the entire reenforced stripe may be of any suitable width. Preferably, however, the stripe is relatively narrow and, as hereinafter pointed out, I am able to make the stripe of the minimum desired width because the line or lines of tuck stitches forming the mock seam, being formed during the knitting operation, are accurately positioned in a straight line between the edges of the stripe and at equal distances from both edges thereof, as 65 would not with any certainty be the case if a

line of sewing machine stitches were employed instead of the structural variations.

The knitted loops wherinto the auxiliary yarn or thread 6 is introduced are desirably plain loops outside of the tuck stitches and are such as are formed in regular knitting. At the back median line of the stocking 1 form, during the knitting operation, a mock seam by some suitable structural variation in the fabric such, for example, as two lines or wales of tuck stitches indicated at 7, 8 between which may be a line of plain stitches 9, the reenforcing yarn or thread 6 being inter-knitted as shown into said lines of tuck stitches 7, 8 and into the line of plain stitches 9 if the latter be present. My invention is not limited to the employment of a plurality of lines or wales of tuck stitches as in certain cases a single line or wale may be sufficient and the structural variation may be of any other suitable character that will constitute a satisfactory mock seam as for example draw stitches. Draw stitches for such purpose are indicated in Fig. 1^a, where the numerals 5 and 6 indicate the main yarn and auxiliary yarn respectively, and the numerals 8' and 9' indicate respectively the portions of said yarns entering into the loops of the draw stitches.

Viewing Fig. 2, it will be observed that the auxiliary yarn or thread is incorporated into the lines of tuck stitches 7 and 8 so that said tuck stitches are so nearly closed by the reenforcing thread that when the stocking is worn the tuck stitches are not sufficiently opened up or stretched to expose the flesh. Moreover the introduction of the reenforcing yarn or thread into the tuck stitches enlarges, to that extent, the mock seam and therefore more nearly simulates the real seam joining the selvage edges of a full fashioned stocking.

Desirably at one outer edge of the stripe, namely, the second formed edge thereof, the auxiliary yarn or thread is floated back to the opposite or first formed edge as indicated at 10 in Fig. 2, so that the floated portions of the auxiliary yarn or thread lie against the inside of the fabric and, being of short length with relation to the entire circumference of the stocking, they are not removed, but being permitted to remain, they enhance or consolidate the stripe appearance and even give a backing to the line or lines of tuck stitches or other structural variations constituting the mock seam.

It will be evident that the line or lines of tuck stitches simulate the actual seam at the back of the leg of a full fashioned stocking and that the stripe simulates the reinforced selvaged edges characteristic of many full fashioned stocking legs.

Where the structural variations which simulate the mock seam are composed of two rows of tuck stitches or other distinguishing

loops, it is obvious that these two rows of tuck stitches need not be separated by a row or rows of regular loops as shown at 9 in Fig. 2, but they may be placed close together or adjoining in the manner indicated in Fig. 3 wherein the two rows of tuck stitches are shown at 11, 12, the regular and auxiliary yarns or threads at 13, 14 respectively, and the floated portions of the reenforcing yarn 10 or thread at 15. It will be observed that the reenforcing yarn 14 is inter-knitted into and forms a structural part of all of the tuck stitches.

Within the scope and purpose of my invention one of said rows of tuck stitches may be omitted and a single row of tuck or other distinguishing stitches may be employed to simulate the mock seam, though this form of my invention lacks certain qualities of the forms already described and, in Fig. 4 I have shown an example of this form wherein the main and reenforcing yarns or threads are indicated respectively at 16, 17 and the line of tuck stitches at 18, it being observed that the reenforcing yarn or thread is floated from edge to edge only of the stripe upon the inner face of the fabric as indicated at 19.

In Fig. 5 I have illustrated a slightly modified form of my invention which, in some respects, is similar to that form shown in Fig. 2. In this form the lines of stitches 7', 8' contain tuck stitches each of which receives yarns or threads from three plain loops instead of from two as in Fig. 2 and furthermore the tuck stitches of each wale alternate with at least one plain loop as shown at 20. Obviously my invention is not limited to the disclosures made.

Obviously my invention may be employed at any suitable part of the stocking or other fabric and may extend through any suitable part thereof. For example it may extend from the top of the heel a part way toward the top of the stocking.

Inasmuch as the floating threads are not sewed down between the two edges of the entire stripe and are not otherwise secured to the fabric between the said edges, the transverse elasticity of the knitted portion of the fabric between said edges or elsewhere is in no way impaired and the float threads occupy such a relatively small part of the circumference of the stocking or other fabric, that they do not impair its transverse elasticity. By employing a mock seam of tuck stitches or other structural variations I do not impair the longitudinal elasticity of the stocking as is the case where a mock seam of sewing machine stitches is employed.

I have referred to the fact that a mock seam formed by a structural variation of the fabric and not by a sewed line of sewing machine stitches possesses certain distinct

advantages. Among said advantages are the following: Said structural variation mock seam centers the seam with respect to the edges of the stripe and insures a perfectly straight seam. It permits the employment of a narrower stripe because of the certainty that the seam is centered with respect to the edges of the stripe. There is no weakening of the yarn or thread of the fabric by the piercing thereof by a sewing machine needle as is inevitably the case where a line of sewing machine stitches is sewed into the fabric. The extra step of running the stocking after completion through a sewing machine to place a line of sewing machine stitches therein is wholly avoided and this very considerably lessens the expense of production and especially where the production is great. There is no puckering or bunching or grouping of the floating threads by reason of the presence of the tuck stitches, as is necessarily the case where a sewed line of sewing machine stitches is run through the stripe and the floating threads at the back thereof. If a line of sewing machine stitches were employed and the same passed through the float threads, it is evident that the latter must of necessity be drawn out of true parallel lines with respect to each other, by the sewing machine needle or other parts of the sewing machine. By employing the structural variation mock seam all of the floated portions extend straight across from edge to edge of the stripe. This is particularly important in the case of thin or sheer stockings as in such stockings the bunched appearance of floated threads is very noticeable. Furthermore the employment of a structural variation mock seam eliminates or minimizes waste due to the difficulty of running a sewing machine line of stitches through a loose reenforcement—that is one having floated threads.

It is clearly to be understood that my invention may be incorporated in knitted fabric other than stockings and hose.

Having thus described certain specific embodiments of my invention and the best mode known to me for producing the same, I desire it to be understood that although specific terms are employed, they are used in a generic and descriptive sense and not for the purpose of limitation, the scope of the invention being set forth in the following claims.

Claims:

1. A so-called seamless knitted stocking composed of a main yarn or thread having a structural stitch variation formed by said main yarn or thread extending through a substantial part of the stocking, the adjoining part of the stocking and said structural variation thereof having an auxiliary yarn or thread incorporated thereinto so as with

- 41
- 5 said structural stitch variation to constitute a simulation of a seamed reenforced selvage of a full fashioned stocking, said structural 65
5 and substantially closed mock seam because of the incorporation of the reenforcing yarn or thread into said seam.
- 10 2. A so-called seamless knitted stocking composed of a main yarn or thread, said stocking having at the back of the leg, a 70
15 mock seam extending lengthwise thereof, said mock seam being composed of a structural stitch variation in the said main yarn or thread, said stocking having, at the back 75
15 of the leg thereof, a stripe composed of the said main yarn or thread and a reenforcing 80
20 yarn or thread, the latter being incorporated into the structure of the said variation.
- 25 3. A so-called seamless stocking having at the back of the leg, a longitudinally extending line of tuck stitches constituting a mock 85
25 seam, and at each side of and incorporated into said line of tuck stitches, a knitted-in auxiliary thread providing a stripe paralleling and embracing said line of tuck 90
30 stitches and cooperating therewith to produce a simulation of the seamed reenforced selvage of a full fashioned stocking, said mock seam being emphasized and rendered 95
35 substantially closed in use by the presence of said knitted-in auxiliary thread.
- 35 4. A so-called seamless stocking having at the back of the leg, a longitudinally extending line of tuck stitches constituting a mock 100
35 seam and a stripe substantially paralleling said line of tuck stitches at each side thereof and also incorporated into the substance of 105
40 said tuck stitches, and composed of that portion of the main yarn and an auxiliary yarn 110
45 knitted in with the main yarn at each side of the line of tuck stitches and also into said tuck stitches, thereby producing a simulation of the seamed reenforced selvage of 115
50 a full fashioned stocking having a seam enlarged and rendered closed in use by the presence of the auxiliary yarn interknitted 120
55 into said tuck stitches.
- 55 5. A so-called seamless stocking having at the back of the leg a longitudinally extending 125
55 duplex line of tuck stitches constituting a mock seam and at each side thereof and incorporated into said mock seam a stripe composed of that portion of the main yarn and an auxiliary yarn knitted in with the main 130
60 yarn at each side of and also into the line of tuck stitches but floated across said tuck stitches at the inside of the stocking from the edges of the stripe, thereby producing a simulation of the seamed reenforced selvage of a full fashioned stocking, said auxiliary 135
65 yarn enlarging the line of tuck stitches and rendering said tuck stitches substantially closed in use.
6. That method of knitting which comprises knitting a plain fabric from a main 140
65 yarn or thread but providing structural 70
70 stitch variations in said main yarn or thread during the knitting and incorporating an auxiliary yarn or thread during the knitting operation by knitting in the same at 75
75 that part of the fabric adjoining the structural stitch variation and also into said structural stitch variation so as to constitute a simulation of a reenforced seamed fabric.
7. That method of knitting a so-called 80
80 seamless stocking including a leg portion having a simulated seamed reenforced selvage, including knitting a mock seam coincidentally with the knitting of the leg portion, and coincidentally with the knitting, introducing an auxiliary yarn at both sides of 85
85 and into said mock seam throughout an area substantially paralleling said mock seam.
8. That method of knitting a so-called 90
90 seamless stocking including a leg portion having a simulated seamed reenforced selvage, including knitting a mock seam at the back of the leg of a stocking coincidentally with the knitting of the leg and introducing an auxiliary yarn at both sides of and into 95
95 said mock seam from substantially the upper end of the stocking to the heel portion throughout a width corresponding to the reinforced selvaged part of a full fashioned stocking leg and floating the auxiliary yarn 100
100 from edge to edge of the reinforcement.
9. That method of knitting a so-called 105
105 seamless stocking including a leg portion having a simulated, seamed reenforced selvage, including knitting the leg portion with 110
110 a line of tuck stitches down the back of the leg and during the knitting introducing an auxiliary yarn or thread with the main yarn or thread at each side of and into said line 115
115 of tuck stitches from substantially the upper end of the stocking to the heel portion throughout a relatively narrow area to correspond to the reinforced selvaged portion 120
120 of a full fashioned stocking leg and floating the auxiliary yarn or thread in each course 125
125 from edge to edge of said reinforced area but without the incorporation of said floating thread into the tuck stitches.
10. A so-called seamless knitted stocking having a leg portion provided at the back 130
130 with a simulated seamed reinforced selvage composed of a mock seam formed from the main yarn of the stocking, and an auxiliary yarn knitted in with said main yarn both in the said mock seam and at the sides of 135
135 said mock seam, throughout an area substantially paralleling said mock seam.
- In testimony whereof, I have signed my name to this specification.

RUFUS W. SCOTT.
